[57] **CLAIM**

The ornamental design for a computer pointing device, as shown and described.

DESCRIPTION

FIG. 1 is a perspective view of a computer pointing device showing my new design;

FIG. 2 is a top view thereof;

FIG. 3 is a bottom view thereof;

FIG. 4 is a side elevation view of one side thereof;

FIG. 5 is a side elevation view of the opposite side thereof; and,

FIG. 6 is a front elevational view thereof, the rear elevational view is a mirror image.

The broken line drawing of part of a cord in FIGS. 1-3 is for illustrative purposes only and forms no part of the claimed design.
